BOX TOOL

Karl Fellroth, Minneapolis, Minn.

Application July 30, 1945, Serial No. 607,832

1 Claim. (Cl. 82—35)

1

My invention relates to improvements in box tools and, more particularly, to a three-roller pressure system for a box tool.

It is well known that in the ordinary two roller box tool, the cutting bit is a part of the pressure system for holding stock while it is being turned.

The principal object of my invention is to provide a three-roller pressure system and eliminate the use of the cutting bit as a part of this system. By eliminating the cutting bit from the pressure system, said bit may be adjusted without upsetting the adjustment of the rollers. This three-roller pressure system gives rigid support to stock being turned and prevents the stock from turning into and out of concentricity.

A further object of this invention is to mount the cutting bit parallel to the cut being made thereby and thus eliminate the difficulty of correctly grinding the cutting bit, as is in the case of the ordinary box tool in which the cutting bit is at an angle to the cut, and requires a highly skilled, well experienced artisan to grind the same. The manner in which my cutting bit is mounted, relative to the cut, only requires the grinding thereof, with an ordinary chip breaker with proper rakes and clearances.

By eliminating the cutting bit, as a part of the pressure system, an exceedingly heavy cut may be taken with true concentricity of the cut. The three-roller pressure system permits the rollers to be adjusted onto the stock to put a high burnish thereon. This three-roller system also eliminates the necessity for releasing the lever on box tools because the three rollers exert pressure on the stock and therefore, when properly adjusted, do not leave tool marks on the cut surface of the stock when drawing the tool back from its work.

These and other objects of the invention will be apparent from the following description, reference being had to the drawings:

To the above end, generally stated, the invention consists of the novel devices and combination of devices hereinafter described and defined in the claim.

In the accompanying drawings, which illustrate the invention, like characters indicate like parts throughout the several views.

Referring to the drawings:

Fig. 1 is a front elevation of the improved box tool;

Fig. 2 is a bottom plan view of the same;

Fig. 3 is a left-hand side elevation of the box tool, as shown in Fig. 1, with some parts broken away and other parts sectioned;

Fig. 4 is a view partly in plan, but principally in horizontal section taken horizontally through the box tool at different elevations; and

Fig. 5 is a fragmentary detail view partly in side elevation and partly in vertical section taken on the line 5—5 of Fig. 1.

The numeral 6 indicates the head of my improved box tool A, which, as shown, is formed of

2

a flat vertically disposed relatively narrow rectangular block of metal. In the center of the head 6 is an annular work opening 7 that extends completely through said head from the front to the back thereof. The lower corners of the head 6, that extend from the front to the back thereof, are rounded at 8 and the overlying portions of the top of the head 6 are outwardly and downwardly inclined to afford bearing surfaces 9, for a purpose which will presently appear.

Two chip escape passageways 10 and 11 in the face of the head 6 extend to the back of said head. These two passageways 10 and 11 lead from the work opening 7, on opposite sides thereof and extend outwardly and downwardly, the former on the right-hand side of the head 6 and the latter on the left-hand side thereof. The passageways 10 and 11 also afford sight openings into the work opening 7.

On the back of the head 6 and integral therewith is a rear extension 12 comprising laterally spaced side members 13 and a back member 14. This rear extension 12 forms a large rectangular vertical opening 15 at the back of the head 6. The head 6 extends materially above and below the rear extension 12 and the outer faces of the side members 13 are flush with the sides of the head 6.

A hollow round shank 16, for mounting the box tool A on a lathe turret or tailstock, has one of its end portions tightly fitted in a hole in the back member 14 with said shank axially aligned with the axis of the work opening 7. An annular flange 17, integral with the shank 16, bears against the back member 14 and is detachably secured thereto by three cap screws 18.

A relatively long cutting or tool bit 19 is mounted in a seat 20 in a boss 21 on the head 6. This boss 21 extends forwardly of the face of the head 6 and outwardly from the right-hand side of said head. The tool bit 19 is rectangular in cross-section and has a close working fit with the seat 20 on all sides thereof. This seat 20 is in the form of a long passageway which extends horizontally and transversely of the work opening 7 and opens through the wall of said work opening. The cutting edge of the tool bit 19 is at the upper side thereof and said upper side is on a radial line extending from the axis of the work opening 7. In other words, the tool bit 19 is parallel to the cut made thereby.

To adjust the tool bit 19 toward its work, I provide a thumb-screw 22 having threaded engagement with the boss 21. This thumb-screw 22 is in axial alignment with the tool bit 19 and impinges the outer end thereof. The tool bit 19 is positively held where adjusted by two set-screws 23 and 24 having threaded engagement with the boss 21. These set-screws 23 and 24 extend at right angles to each other, with the former impinging the outer side of the tool bit 19.

and the latter impinging the under side thereof. The thumb-screw 22 is positively held where adjusted by a set-screw 25 having threaded engagement with the boss 21 on its under side. A brass plug 26 is interposed between the thumb-screw 22 and the set-screw 25 to prevent said set-screw from mutilating the thread of the thumb screw 22.

A vertical sight opening 27 extends through the boss 21 to expose the contacting end portions of the tool bit 19 and the thumb-screw 22. In actual construction, the thumb-screw 22 will have a micrometer adjustment. It may be here stated that the tool bit 19 will, of course, be ground with the customary chip breaker on its upper edge and with the proper rakes and clearances.

My invention includes a three-roller pressure system; two upper rollers and a lower roller 28. Each roller 28 is mounted on a carrier 29, in the form of an elongated block, slidably mounted in a channel guide 30 in the face of the head 6. The carriers 29 are bifurcated at their inner end portions to afford pairs of bearing lugs 31 between which the rollers 28 rotate. Said rollers 28 are journaled on studs 32 that extend through aligned holes in the pairs of bearing lugs 31. Long set-screws 33 extend longitudinally into the carrier 29 from the outer ends thereof, have threaded engagement therewith, impinge the studs 32 and rigidly hold the same in the bearing lugs 31.

One side of each channel guide 30 is perpendicular to the face of the head 6 and the other side thereof is inwardly and outwardly inclined. The carriers 29 slidably rest on the bottoms of the channel guides 30 and their sides have a close working fit with the sides of said guides. In the perpendicular side of each carrier 29 is a longitudinal groove 34. Each carrier 29 is positively held where adjusted in its channel guide 30 by a set-screw 35 having threaded engagement with the head 6, extends into the respective groove 34 and impinges said carrier. The purpose of the grooves 34 is to prevent the set-screws 35 from mutilating the carriers 39 where they would have sliding contact with the respective sides of the channel guides 30.

The two upper channel guides 30 are in upwardly diverging relation and extend on angles of about thirty-two degrees from a vertical plane passing through the axis of the working opening 7. When the rollers 28 are adjusted to their innermost positions, they are close to each other and to the axis of said work opening. This relative arrangement of the two upper rollers 28 makes it possible for them to hold stock of a relatively small diameter. The lower guide channel 30 is in a vertical plane passing through the axis of the work opening 7 and midway between the two upper rollers 28.

The rollers 28 and the tool bit 19 are in the same vertical plane and the outer faces of said rollers are very close to the cutting point on said bit which is on its upper outer corner, see Fig. 3. Due to the close proximity of the rollers 28 to the tool bit 19, only a very slight cut is made in the stock being turned before said stock is fed between said rollers. As soon as the stock enters between the rollers 28, the operator first adjusts the two upper rollers 28, as will presently appear, into engagement with the turning stock and rotated thereby. Next, the lower roller 28 is adjusted into engagement with the stock and rotated thereby. Obviously, the three-point circumferential contact of the rollers 28 with the

stock positively holds said stock against movement into and out of concentricity.

Each carrier 29 is moved endwise in its channel guide 30 by a long adjusting screw 36, having threaded engagement with a nut-acting lug 37 on the bottom of said carrier. The lugs 37 work in deep grooves 38 into the bottoms of the channel guides 30. The outer end portions of the adjusting screws 36 are smooth and turnably mounted in bushings 39 in bearing plates 40. These bearing plates 40 are secured to the head 6 by pairs of cap-screws 41 and the two upper bearing plates 40 are in the surfaces 9. On the inner end of each adjusting screw 36 is a pilot pin 42 that extends through a hole in the wall of the head 6 between the work opening 7 and the inner end of the respective groove 34. A collar 43 on each adjusting screw 36 is engaged by the respective bushing 39. The adjusting screws 36 are held against endwise movement by the head 6 at the inner end of the grooves 34 and the bushings 39. The bushings 39 are positively held where endwise adjusted in the bearing plates 40 by set-screw 44, see Fig. 5. A brass plug 45 is interposed between the set-screws 44 and the bushings 39 and thereby prevents mutilation of the bushing 39 which would interfere with their free sliding movement in the bearing plates 40.

In the end portion of each carrier 29 is a lubricating element 46.

The drawings illustrate a commercial form of the invention, but it will be understood that the same is capable of certain modifications as to details of construction, arrangement and combination of parts within the scope of the invention herein disclosed.

What I claim is:

In a box tool, a head having in its face a work opening, three radially disposed channel guides in the face of the head and having open ends, two of the channel guides being in close proximity and the other channel guide being substantially diametrically opposite a medial point between said two channel guides, a carrier slidably mounted in each channel guide, three rollers journaled, one on the inner end of each carrier for holding a piece of stock therebetween, at circumferentially spaced points, a nut-acting lug on each carrier, an adjusting screw having threaded engagement with said lug, a displaceable bearing plate closing the outer end of each channel guide, an adjustable bushing in each bearing plate in which the adjusting screw is turnably mounted, said adjusting screws being held by the head and the bushings against endwise movement, means for locking the bushings in the bearing plates, and a tool bit mounted on the head for cutting the stock.
